UNITED STATES PATENT OFFICE.

AMOS REEVES AND ALFRED W. JOHNSON, OF ROCK FALLS, ILLINOIS.

DESIGN FOR A MEMBER FOR CLOTHES-TONGS.

SPECIFICATION forming part of Design No. 30,479, dated April 4, 1899.

Application filed March 10, 1899. Serial No. 708,607. Term of patent 7 years.

To all whom it may concern:

Be it known that we, AMOS REEVES and ALFRED W. JOHNSON, citizens of the United States, residing in the city of Rock Falls, county of Whiteside, and States of Illinois, have invented and produced a new and original Design for a Member for Clothes-Tongs, of which the following is a specification, reference being had to the accompanying drawings, forming part thereof.

Figure 1 is a side elevation of our invention. Fig. 2 is a plan of the same.

As shown in the drawings, the leading features of our design are the coils which form part of the hinge, the curved jaw, and the twisted handle.

B designates the twisted handle.

C designates the coils, and E the curved jaw.

The entire member is formed by the bending of one wire into the design, as shown, and A designates a loop formed at the opposite end of the handle from the jaw, where the ends of the wire meet.

What we claim is—

The design for a member for clothes-tongs substantially as herein shown and described.

In testimony whereof we affix our signatures in the presence of two witnesses.

AMOS REEVES.

ALFRED W. JOHNSON.

Witnesses:

C. L. MANAHAN,

M. T. MANAHAN.
